UNITED STATES PATENT OFFICE.

HARRY A. SHIELDS, OF GRAND RAPIDS, MICHIGAN.

MACHINE FOR TURNING TUBULAR FABRICS.

1,080,336.

Specification of Letters Patent. Patented June 25, 1912.

Application filed December 15, 1911. Serial No. 665,908.

To all whom it may concern:

Be it known that I, HARRY A. SHIELDS, a citizen of the United States of America, residing at Grand Rapids, in the county of Kent and State of Michigan, have invented certain new and useful Improvements in Machines for Turning Tubular Fabrics; and I do hereby declare the following to be a full, clear, and exact description of 10 the invention, such as will enable others skilled in the art to which it appertains to make and use the same.

My invention relates to improvements in machines for turning a tubular fabric inside out and its object is to provide a device which will accomplish this operation in the simplest way and which will handle the material with the least possible wear and stretching effect and to provide the device 20 with various new and useful features as hereinafter more fully described and particularly pointed out in the claims.

It is the custom in the manufacture of 25 knit fabric to knit this fabric in the form of a tubular piece of considerable length. After it has been knit in this shape it is flattened out and rolled up for convenience in handling. This knit fabric is generally washed and sometimes napped and during 30 this process the fabric must be turned with the original inner side outward for various reasons well known to the manufacturer.

The object of my newly invented device is to turn this tubular piece of fabric so 35 that it may be washed and napped and after it has undergone this process it is again run through the machine to return it to its original condition.

Referring to the accompanying drawings: 40 Figure 1 is a side elevation of a device embodying my invention; Fig. 2 is a horizontal section taken in the plane of the axis of the tube; Fig. 3 is an enlarged sectional elevation of the feeding and turning portion of 45 this device; Fig. 4 is an end view of the tube showing the turning rolls with portions broken away; Fig. 5 is a horizontal section on the line 5—5 of Fig. 3; Fig. 6 is a transverse vertical section 50 through the axis of the feeding rolls; and Fig. 7 is an elevation of the driving mechanism showing the manner in which the driving rollers are mounted and the means for

moving them to and from each other to grip the fabric. 55

Like numbers refer to like parts in all of the figures.

1 is a tube of considerable length preferably horizontally disposed and supported at one end only in a frame 2 which surrounds and is clamped firmly about it. The unsupported end of this tube is provided with a sleeve member 3 in which are mounted two cylindrical feed rollers 4 projecting through openings in opposite sides of the coupling. These feed rollers are journaled on vertical shafts 5, slidably mounted in supports having slots 6 and 7 extending transversely of the tube. This slideable mounting of the shaft 5 allows the rollers 4 a movement toward and from each other. The feed rollers 4 are driven by friction transmitted through the fabric between them and the driving rollers 8 which latter are mounted on vertically disposed shafts 60 9 journaled in bearings 10 in frames 11, pivotally supported at their respective lower ends on a base plate 12 allowing the driving rollers 8 on the upper ends of the shafts 70 a swinging movement to and from each other. 75

Pulleys 13 are fixed on the shafts 9 and these shafts are rotated by any convenient driving belt, (not shown). The swinging movement of the rollers 8 is controlled by 85 means of a shaft 14 which is provided at its respective ends with right and left hand threads which engage nuts 15, one of which is pivotally attached to each of the frames 11.

A guide flange 16 is centrally mounted 90 upon the shaft 14 and turns in a slotted projection 17 attached to the base plate 12. This guide flange 16 prevents any longitudinal play of the shaft, thus keeping the train of rollers properly positioned at all 95 times. A hand wheel 18 is mounted on the shaft by means of which the shaft may be rotated to swing the rollers 8 to or from each other. The extreme unsupported end of the tube 1 terminates in a tubular member 19 and is provided at its outer end with turning rollers 20 preferably four in number arranged as shown and journaled on shafts 21 which are mounted in brackets 22 attached to the end of the tubular member 100 19. These turning rollers serve to guide 105

the fabric as it passes over them and is turned inside out. The sleeve 3 is provided with a funnel shaped inlet passage 23 which tends to guide the tubular fabric centrally between the feed rollers 4. The lower edge of this funnel shaped passage is raised from the bottom of the tube to guide the fabric upward and hold it well toward the center of the rolls so that it will not slip down and become entangled in the edges of the same.

A guide roller 24 is located at the inlet or supported end of the tube 1 to guide the fabric as it enters the tube.

15 The operation of the machine is as follows: The tubular knit fabric as before stated is folded flat and rolled at the knitting machine. This roll of flattened fabric is mounted in any convenient way near the 20 inlet end of the tube 1 so that it may be unrolled and drawn through the tube. The flattened fabric passes over the guide roller 24 is drawn through the tube 1 gradually assuming a rope shape and is guided between the feed rollers 4 by the funnel shaped 25 inlet 23. After the fabric has passed between the feeding rollers it is drawn through to the end of the tubular member 19 and turned back outside of this member 19 and turned back outside of this member 30 over the turning rollers 20. It is then brought back until it is gripped between the driving rollers 8 and the feed rollers 4 outside of the tube. After the fabric has thus been started in the machine power is 35 then applied to rotate the driving rollers 8 which will in turn drive the rollers 4 which latter rollers will draw the fabric through the tube 1 and feed it toward the end of the tube so that it will pass loosely over the 40 turning rollers 20 and turn back outside the tube to the driving rollers 8 and the feed rollers 4 which slide it back over the tube 1. The machine is run until the entire piece of 45 knitted fabric is thus drawn through the tube, turned inside out over the end of the same and deposited around the outside of the tube by the driving rollers. It will be seen that the fabric is now turned as desired and after this operation is completed 50 the feeding rollers 8 are swung apart and the fabric may now be drawn off the end of the tube and folded or otherwise disposed of.

One of the important features of this device is that the fabric is fed loosely over the 55 turning rollers 20 so that it is not strained or distorted in this operation and there is also no strain on the fabric as it is drawn from the tube after it has been turned.

In order to enable this device to successfully operate on fabric of a greater width the tubular termination 19 which carries the turning rollers 20 may be removed and a similar one having a diverging opening applied in the place of the one shown. 65 This diverging or enlarged opening is prac-

tically identical with the one shown except that the turning rollers are spaced farther apart and the circumference at its mouth is greater so that the fabric of greater width will turn backward over the rollers without 70 wrinkling.

What I claim is:—

1. A machine for turning tubular fabrics comprising a tubular structure, means for turning the fabric over the end of said 75 structure, feed rollers within the structure adapted to move the fabric longitudinally within said structure and means for rotating said rollers.

2. A machine for turning tubular fabrics comprising a tubular structure, means for moving the fabric in one direction upon the outside of the structure, and means within the structure for moving the fabric in the opposite direction in the interior of 80 85 said structure.

3. A machine for turning tubular fabrics comprising a tubular structure supported at one end, a pair of rollers within the same to engage the fabric therebetween and move 90 the same toward the unsupported end of the structure, and a pair of rollers on the outside of the structure to engage the fabric and move the same away from said end.

4. A machine for turning tubular fabrics, comprising means over which the fabric is reversed, a pair of feed rollers adapted to engage the outside of the fabric and move the same toward the said means, means for pressing the fabric against the outer sides of 95 100 said feed rollers after it has been turned to move the same away from the means over which the fabric has been turned, means for supporting all of said rollers in operative position and means for rotating said feed 105 rollers.

5. A machine for turning tubular fabrics, comprising a series of four rollers arranged substantially in a row side by side and in close relation, the two inner rollers engaging 110 one side of the fabric and moving the same in one direction and also engaging the same side of the fabric after it has been reversed to move the same in the opposite direction, means for pressing the outer roller toward the outer sides of the inner rollers, means for supporting the rollers in place over the end of which means the fabric is turned and means for rotating the rollers.

6. A machine for turning tubular fabrics, 115 comprising a tubular structure having opposing side openings, inner rollers adapted to engage the fabric therebetween and move the same in one direction and outer rollers adapted to again engage the fabric with the inner rollers, and feed the fabric in the opposite direction.

7. A machine for turning tubular fabrics, comprising a tubular structure having a projecting open end and opposing side 120 125 130

- openings, inner rollers within the tube to engage the fabric therebetween and feed the same toward said end of the structure, outer rollers engaging the fabric with the outer 5 sides of the inner rollers to move the fabric away from said end and means for rotating said rollers.
8. A machine for turning tubular fabrics, comprising a tubular structure having an 10 open projecting end and side openings, a series of four rollers arranged in a line transversely of said structure and extending through said opening, said rollers being normally in close relation and separable, the inner 15 rollers adapted to oppositely engage the fabric and move the same toward the said open end, over which end the fabric is turned, the outer rollers being adapted to engage the fabric with the outer sides of the inner 20 rollers to move the fabric in the opposite direction and means for rotating the outer rollers.
9. A machine for turning tubular fabrics, comprising a tubular structure having a 25 projecting open end and opposing side openings, rollers supported on said end and arranged in circular relation, feed rollers in said structure opposite said openings and movable toward and away from each other 30 and also adapted to engage the fabric therebetween and feed the same toward said open end, outer rollers oppositely pressing the fabric against the outer sides of the respective inner rollers to move the same away 35 from said end, means for moving the outer rollers toward and away from the inner rollers and means for rotating the outer rollers.
10. A machine for turning tubular fabrics, comprising a tubular structure supported at one end only and having openings 40 in its opposite sides, inner rollers in said structure opposite said openings and movable toward and away from each other to engage the fabric therebetween, a tapered tube or funnel in said structure near the said rollers, driving rollers engaging the inner rollers, means for moving said driving 45
- rollers toward and away from the inner rollers and means for rotating the driving 50 rollers.
11. A machine for turning tubular fabrics, comprising a tube having a projecting open end, a coupling in the tube having openings in its opposite sides, inner rollers 55 mounted within said coupling adapted to engage the fabric therebetween, a detachable extension of the tube carried by said coupling, turning rollers on the end of the extension, driving rollers adjustable toward 60 and from the feed rollers and means for rotating the driving rollers.
12. A machine for turning tubular fabrics, comprising a tubular structure having a projected open end and provided with 65 openings in its opposite sides, inner rollers opposite said openings adapted to engage the fabric therebetween, turning rollers mounted on the projecting end of the structure, outer rollers opposite the inner rollers, 70 pivoted frames carrying the outer rollers, a right and left hand screw engaging nuts pivoted in the respective frames, a flange on the screw, a slotted projection engaging the flange and means for rotating the outer 75 rollers.
13. A machine for turning tubular fabrics, comprising a tubular structure supported at one end only and provided with openings in its opposite sides, feed rollers in 80 said structure opposite the openings, a cone or funnel in the structure near the feed rollers, turning rollers mounted on the unsupported end of the structure, driving rollers opposite the feed rollers, movable frames 85 supporting the driving rollers, means for adjusting the frames toward and away from each other and means for rotating the rollers.

In testimony whereof I affix my signature 90 in presence of two witnesses.
